UNITED STATES PATENT OFFICE.

GEORGE HENRY WHEARY, OF RACINE, WISCONSIN.

FOLDABLE GARMENT-HANGER FIXTURE.

1,262,606.

Specification of Letters Patent. Patented Apr. 9, 1918.

Application filed July 6, 1914. Serial No. 849,041.

To all whom it may concern:

Be it known that I, GEORGE HENRY WHEARY, a citizen of the United States, and resident of Racine, in the county of Racine 5 and State of Wisconsin, have invented new and useful Improvements in Foldable Garment-Hanger Fixtures, of which the following is a description, reference being had to the accompanying drawings, which are a 10 part of this specification.

This invention relates to improvements in foldable garment hanger fixtures.

It is one of the objects of the present invention to provide a foldable garment 15 hanger fixture which may be secured to one of the side walls or to the inner side of the door of a closet so that removable garment hanger tracks used in trunks may be transferred from the trunks to the fixture and 20 have garment hangers mounted thereon.

A further object of the invention is to provide a foldable garment hanger fixture which may be easily carried in a trunk in order to permit the use of the trunk tracks 25 and garment hangers outside of the trunk.

A further object of the invention is to provide a foldable garment hanger fixture in which the foldable arms of the fixture are locked in open position by the means securing the fixture to a support.

A further object of the invention is to provide a foldable garment hanger fixture in which the garment hanger tracks thereof may be extended to permit the separation of 35 the garment hangers mounted on the tracks.

A further object of the invention is to provide a foldable garment hanger fixture in which the securing means may be used as garment hooks.

A further object of the invention is to provide a foldable garment hanger fixture which is of simple construction, is strong and durable and is well adapted for the purpose described.

With the above and other objects in view, the invention consists of the improved foldable garment hanger fixture and its parts and combinations as set forth in the claims, and all equivalents thereof.

In the accompanying drawing in which the same reference characters indicate the same parts in all of the views:

Figure 1 is a top view of the improved foldable garment hanger fixture shown attached to a support;

Fig. 2 is a top view of a portion of the fixture shown in folded position;

Fig. 3 is a sectional view of the fixture taken on line 3—3 of Fig. 1, the track portions of the fixture having been removed; 60

Fig. 4 is a sectional detail view taken on line 4—4 of Fig. 1;

Fig. 5 is a top view of a modified form of fixture in which the tracks are combined with the frame of the fixture; 65

Fig. 6 is a sectional view thereof taken on line 6—6 of Fig. 5; and

Fig. 7 is a sectional detail view taken on line 7—7 of Fig. 6.

Referring to the drawing the numeral 8 70 indicates a support and 9 the improved foldable garment hanger fixture mounted thereon. The fixture comprises a foldable U-shaped band 10 which is removably connected to a support by holding members or 75 screws 11. The members or screws have annular recessed heads 12 which are engaged by the recessed portions 13 of the right angle extensions 14 of the side arms or stems 15. The rear ends of the side arms have hinged 80 connections 16 with the outer end portions of the rear or spacing portion 17 of the band and when the side arms are in unfolded positions the angular extensions 14 are in longitudinal alignment with the said 85 spacing portion. When the extensions engage the holding screws the side arms will be held rigidly in unfolded or outstanding positions. A pivoted U-shaped locking member 18 is provided on the band for locking 90 the side arms in closed position. Hooks 19 are formed on the heads of the holding screws to adapt them to hold garments when not engaged by the U-shaped band.

Tracks 20 formed of metal rods have annular recesses 21 extending around their inner ends and the recessed portions of said tracks on one side are slabbed as indicated by the numeral 22 to permit the said recessed portions to enter the locking recesses 100 23 formed in the spacing member 17. The lower portion 23' of each recess 23 is of circular form corresponding in diameter to the diameter of the recessed portions of the tracks, while the upper or entrance portion 105 24 of the recess is of less width than the lower portion and corresponds in width to the transverse thickness of the slabbed portions of the tracks. This construction permits the recessed and slabbed portions of 110

the tracks to enter the recesses and by giving a quarter turn to the tracks to turn the slabbed portions of the tracks out of register with the entrance recesses, the tracks will be securely locked to the band at their rear or inner ends.

The outer side end portions of the tracks are provided with curved laterally-extending plates 25 having hook-like end portions 26 which hook over the recessed upper edge portions 27 of the side arms 15 when the tracks are revolved a quarter turn into locking engagement with the spacing portion of the band. These curved plates project outwardly from the tracks in planes at right angles with relation to the planes of the faces of the slabbed portions of the tracks so that when the hooked portions of the plates are revolved to engage the upper edges of the band the rear end portions of the tracks will be locked to the band.

Each curved plate has mounted thereon a spring actuated bolt 28 which projects outwardly therefrom and extends into the locking openings 28' of the band to lock the plates in band engaging position. The plates are unlocked from the band by pressing inwardly on the projecting ends of the spring portions of the bolts.

The recessed portions 27 of the side arms 15 are of a depth corresponding to the thickness of the plates 25 to permit the said plates to enter said recessed portions and to lie flush with the upper edges of the side arms.

The outer end portions of the tracks are provided with extensible tracks 29 hinged thereto which are adapted to swing horizontally outwardly and into longitudinal alignment with the tracks and are respectively connected to permit garment hangers 30 mounted on the inner tracks to be slid outwardly upon the extensible tracks so that garments carried by the hangers may be easily removed or replaced. The outer end portions of the extensible tracks are arranged to overlap and interlock with each other when in closed position.

Knobs 31 projecting from the outer end portions of the extensible tracks serve to prevent the garment hangers 30 from accidentally sliding off the outer ends of the extensible tracks.

The tracks which are adapted to fit corresponding supporting means forming part of a trunk (not shown) may be transferred from the trunk supporting means to the foldable fixture placed in a closet or other place in a very simple manner.

In the modified form shown in Figs. 5, 6 and 7 the foldable frame is omitted and the tracks 32 are formed of metal bars rectangular in cross section and which are provided with slotted offset plates 33 on their inner ends for attachment to the heads of the holding screws 11'. The slotted por-

tions 33' engage the screws in the same manner as the spacing band 17. In the screws shown in this form the garment hooks are omitted but may be used if desired.

The plates 33 are of sufficient width to 70 permit the offset portions 34 of the plates to extend over the opposite sides of the heads of the screws and rest against the support so that a firm bearing is provided for the tracks and the frictional contact of 75 the plates with the supporting wall will prevent the turning of the tracks. These tracks are also provided with hinged extensible tracks 35 which are used in the same manner before described.

From the foregoing description it will be seen that the foldable garment hanger fixture may be carried in a trunk and when the destination is reached the fixture may be mounted in a closet and the garment hangers 85 from the trunk supported thereon in the same manner as supported in a trunk thus permitting the use of the same hangers and tracks outside of the trunk.

What I claim as my invention is:

1. A garment hanger fixture, comprising holding members having recessed portions, a U-shaped foldable member having foldable side arms and outwardly projecting extensions provided with recessed portions 95 which engage the recessed portions of the holding members, said foldable member also having other recessed portions, and garment hanger tracks having recessed portions which slidably engage the last mentioned 100 recessed portions of the foldable member.

2. A garment hanger fixture, comprising holding members having recessed portions, a U-shaped member having foldable side arms and outwardly projecting extensions 105 provided with lower edge recesses which engage the recessed portions of the holding members, said foldable member also having upper edge recesses, and garment hanger tracks having recessed and hooked end portions which engage the last mentioned recessed portions of the foldable member.

3. A garment hanger fixture, comprising holding members having means for attachment to a support and also having recessed 115 portions, a U-shaped member having side stems and recessed portions which engage the recessed portions of the holding members, the side stems of said U-shaped member being hinged to the rear portion thereof, 120 and garment hanger tracks removably connected to the rear and side portions of the U-shaped member.

4. A garment hanger fixture, comprising holding members having means for attachment to a support and also having recessed portions, a rear spacing member, side arms hinged to the outer end portions of the spacing member and having extensions projecting at an angle therefrom which are pro- 130

vided with recessed portions for engaging the recessed portions of the holding members.

5. A garment hanger fixture, comprising holding members having means for attachment to a support and also having side recessed portions, a rear spacing member having recessed portions, side arms hinged to the outer end portions of the spacing member and having extensions projecting at right angles therefrom which are provided with recessed portions for engaging the side recessed portions of the holding member, said recessed engagement locking the side arms in outwardly extended positions, and garment hanger rails engaging the recessed portions of the spacing member and being locked thereto and to the side arms by a revoluble movement.
- 10 6. A garment hanger fixture, comprising holding screws having heads provided with

annular recesses, a rear spacing member, side arms hinged to the outer end portions of the spacing member and having extensions projecting outwardly from the rear end portions thereof which are provided with recesses in their lower edge portions, said recessed portions engaging the annular recesses of the holding screws, said engagement holding the side arms in locked 25 extended positions, garment rails removably connected to the side arms and to the spacing member, and extension rails connected to the outer ends of the removable rails.

In testimony whereof, I affix my signature, in presence of two witnesses.

GEORGE HENRY WHEARY.
